(57) **CLAIM**

The ornamental design for an engine shroud, as shown and described.

DESCRIPTION

FIG. 1 is a perspective view of an engine shroud according to one embodiment of the invention;

FIG. 2 is a top view of the engine shroud of FIG. 1;

FIG. 3 is a bottom view of the engine shroud of FIG. 1;

FIG. 4 is a right side view of the engine shroud of FIG. 1;

FIG. 5 is a left side view of the engine shroud of FIG. 1; and,

FIG. 6 is a front view of the engine shroud of FIG. 1.

The broken line showing of the environment is for illustrative purposes only and forms no part of the claimed design.
